HYDRAULIC CONTROL MECHANISM

Henry W. Landenberger, Philadelphia, Pa., assignor to American Engineering Company, Philadelphia, Pa., a corporation of Pennsylvania

Application March 26, 1935, Serial No. 13,095

4 Claims. (Cl. 60—52)

This invention relates to control mechanisms for pumps, and more particularly to control mechanisms of the hydraulic type.

One object of the present invention is to provide a generally improved control mechanism for pumps which is entirely hydraulic in form.

Another object is to provide a control mechanism for pumps employed in the operation of hydraulic presses and like machines, which functions to maintain the pump on stroke until a predetermined pressure is exceeded whereupon the pump is automatically adjusted to neutral position.

A further object is to provide a control mechanism for pumps employed for operating presses and like machines, which functions in such a manner that when the press platen completes its cycle of operation the pump will be adjusted to neutral stroke position and retained in this position at a relatively low pressure.

Other and further objects will become apparent as the description of the invention progresses.

Of the drawings:

Fig. 1 is a diagrammatic view partly in section showing the control mechanism comprising the present invention.

Fig. 2 is a side elevational view partly in section of the pump and some of the control elements associated therewith.

Fig. 3 is a side elevational view of the pump and control elements shown in Fig. 2.

Referring to the drawings, the numeral 1 designates generally a pump, mounted upon a supply or makeup tank 2. Pump 1 may be of the general type shown and described in the United States Patent to Hele-Shaw No. 1,077,979, which in the present instance is so constructed as to deliver fluid under pressure to pipe 3 and suction to pipe 4. Pipe 3 is operatively connected to a port 5 provided in the lower side of a control valve 6. Control valve 6 comprises a reciprocable valve element 7 having a pair of spaced valve heads 8 and 9 adapted for adjustment by a lever 10 to selectively establish communication between pipe 3 and a pair of pipes 11 and 12. Pipe 11, together with a branch pipe 13, delivers fluid to a pair of pullback motors 14 and 15 of a hydraulic press 16. Pipe 12, on the other hand, communicates with the upper end of a cylinder 17 having a piston 18 operating therein which has secured thereto a connecting rod 19 operatively connected to a movable platen 20 of the hydraulic press 16.

The connecting rods 21 and 22 connected to pistons 23 and 24 of pullback motors 14 and 15 respectively are also operatively connected to plat-

en 20, as shown in Fig. 1. It therefore is seen that when lever 10 is in the full line position shown in Fig. 1, fluid from pump 1 will discharge through pipes 11 and 13 and thereby cause platen 20 to move toward its upper position. On the other hand, when lever 10 is moved to the dotted line position fluid will enter cylinder 17 and thereby cause the platen to move downwardly toward the work.

Valve 6 has also provided therein a passage 25 which communicates with the opposite ends of the chamber in which the valve member 7 operates. Passage 25 also communicates with a pipe 26 to which the suction pipe 4 leading from pump 1 is connected. A check valve 27 is secured to the extreme right hand end (Fig. 1) of pipe 26, and a second pipe 26' connects said valve with makeup tank 2. Check valve 27 prevents the fluid returning to pump 1 through pipes 26 and 4 from flowing to the makeup tank 2 but permits makeup fluid to be drawn into the system in a well known manner. The drive shaft 28 of pump 1 is connected to the armature shaft 29 of an electric motor or any other suitable driving mechanism (not shown) by a coupler 30.

The pressure required to operate certain of the control elements associated with pump 1 is derived from a small auxiliary pump 31, which, as shown in Fig. 1, is connected to the drive shaft 28 by a chain and sprocket mechanism 32. Pump 31 discharges fluid under pressure through a pipe 33 which is connected to a branch pipe 34. The pressure developed by pump 31 is controlled by an adjustable relief valve 30 provided in a bypass pipe 31 which connects pipe 33 with makeup tank 2. One end of pipe 34 is connected to a fluid motor 35 mounted at the right hand side of pump 1 while the other end of said pipe is connected to a port 36 of a valve 37, mounted near the upper end of press 16 in any suitable manner. Referring more particularly to Figs. 2 and 3, it will be seen that pipe 34 is so connected to motor 35 that fluid is delivered to the left hand side of the piston 38 thereof. Motor 35 is secured to the right hand side of casing 39 of pump 1 in any suitable manner, such as by rods 40.

Piston 38 has secured thereto a rod 41 which extends through a gland 42 provided at the left hand end of motor 35, and is secured in any suitable manner to a crosshead 43. The opposite ends of crosshead 43 have secured thereto a pair of guide rods 44 which pass through suitable bearings in the casing 39 and are secured at their inner ends to the sliding blocks or stroke ad-

justing elements 45 of the pump in a well known manner.

The right hand end of motor 35 has secured thereto one end of a second pipe 46, the other end of which is connected to a second port 47 of valve 37. Valve 37 has provided therein a reciprocable valve member 48 having a pair of valve heads 49 and 50. A spring 51 mounted in a casing 52 at the upper end of valve 37 extends between the upper end of said casing and a disc 53 secured to the upper end of a rod 54, the lower end of said rod abutting the upper end of valve member 48. The lower end of valve member 48 has secured thereto a rod or stem 55 extending through an aperture provided in the lower end of valve casing 37 and is adapted to be engaged by platen 20 when the latter approaches the limit of its upward movement. Fig. 1 shows the arrangement of the parts when the platen 20 is out of engagement with rod 55, at which time it will be observed that spring 51 has urged valve member 48 downwardly so that valve heads 49 and 50 prevent communication between pipes 34 and 46. Valve 37 has also provided therein a substantially vertical passage 72 which connects the upper and lower ends of the valve chamber and communicates with a port 73. A pipe 74 secured to and extending between port 73 and makeup tank 2 connects valve 37 to exhaust. When the parts are in this position, the fluid discharging from pump 31 is trapped between these valve heads and as a result fluid pressure is delivered only to the left hand side of piston 38. However, when platen 20 moves upwardly valve member 48 will also be moved upwardly, thereby establishing communication between pipes 34 and 46 and as a result fluid discharging from pump 31 will enter motor 35 through pipes 34 and 46, thereby subjecting both ends of the piston 38 to fluid pressure. Inasmuch as the effective area of the right hand end of piston 38 is greater than that of the left hand end thereof, due to the connection thereto of the connecting rod 41, piston 38 will tend to move to the left, thereby actuating the stroke adjusting elements of pump 1 toward neutral or leakage stroke position. When platen 20 moves downwardly out of engagement with valve stem 55, spring 51 will again urge valve member 48 to the position shown in Fig. 1, whereupon fluid from pump 31 will now discharge to the left hand side only of piston 38, thus causing the latter to move to the right and to again adjust the stroke of the pump to on-stroke position. During movement of piston 38 in this manner the fluid in the chamber at the right hand side thereof will now flow through pipe 46, valve 37, port 73, pipe 74, and thence into makeup tank 2.

Pump 1 has also secured to the left hand side thereof, such as by bolts 57, or any other suitable securing means, a second fluid motor 58. This motor also comprises a cylinder 59 having a piston 60 operating therein. The right hand end of cylinder 60 communicates with a substantially vertical passage 61 extending upwardly from the lower end of the casing and to which one end of a pipe 62 is connected. The other end of pipe 62 is connected to the pressure pipe 3 leading from pump 1. It therefore is seen that motor 58 is at all times connected to the pressure delivered by pump 1. Piston 60 extends through a gland 63 provided at the left hand end of motor 58 and abuts against the right hand side of a crosshead 64. Crosshead 64 has secured to the opposite ends thereof a pair of guide rods 65, the inner

ends of which pass through suitable bearings provided in the left hand side of pump casing 39, and are also secured to the sliding blocks 45, as shown more particularly in Fig. 1. Secured to the opposite ends of a flange 66 of motor 58 are a pair of threaded rods 67. These rods pass through apertures provided in crosshead 64 and have a pair of adjusting nuts 68 secured to the left hand ends thereof. By this construction, it is seen, the extent of movement to the left of the sliding blocks or stroke adjusting elements 45 may be varied to best suit the conditions of operation.

From the foregoing description, the operation of my improved control mechanism is thought to be obvious. However, in order to correlate the various elements thereof, a brief résumé of the operation of the device as a whole will now be given.

Let us assume that the platen 20 is in its uppermost position and that it is desired to begin a new cycle of operation. The operator first grasps lever 10 and moves the same to the dotted line position shown in Fig. 1. The fluid trapped in pullback motors 14 and 15 will now flow through pipes 13 and 11, passage 25, pipe 26, 25 and pipe 4 to pump 1, and platen 20 will gravitate out of engagement with valve stem 55. When this occurs spring 51 will urge valve member 48 to the position shown in Fig. 1. Fluid discharged from pump 31 will now actuate piston 38 and the stroke adjusting means 45 of pump 1 to on-stroke position and as a result fluid under pressure from pump 1 will be delivered to cylinder 17, thereby actuating platen 20 toward the work. As the platen engages the work, the pressure in the system gradually increases and when this pressure exceeds the value determined by the relative sizes of the left hand side of piston 38 operated upon by pump 31, and piston 60 operated upon by the pressure in the system as developed by pump 1, the sliding blocks or stroke adjusting elements 45 of pump 1 will move to the left toward neutral or leakage stroke position. The fluid at the left hand side of piston 38 will now flow through pipes 34, 33 and 71, relief valve 70, and thence into makeup tank 2. The required predetermined pressure may thus be maintained upon the work as long as desired.

When it is desired to remove the material from the press after a pressing operation, the operator simply moves the lever 10 to the full line position shown in Fig. 1. This causes a reduction of the pressure in the system and the fluid from pump 31 will now actuate piston 38 to the right to place pump 1 onstroke. Fluid from pump 1 will now enter pipes 11 and 13, causing platen 20 to be moved upwardly by the operation of pullback motors 14 and 15. The fluid in cylinder 17 will now be forced back through pipe 12, passage 25 of valve 6, and thence to pump 1 through pipes 26 and 4 respectively. As the platen 20 approaches its upper limit of travel it engages valve stem 55, thereby moving valve member 48 upwardly and establishing communication between pipes 34 and 46, and as a result fluid pressure from pump 31 will be delivered to both ends of piston 38. Due to the fact that the right hand end of piston 38 has a greater effective area than the left hand end thereof, and also due to the operation of motor 58, as well as the natural tendency of the pump to assume a neutral position, the sliding blocks or stroke adjusting elements 45 will move to the left toward neutral position. The platen 20 of the press 16 will now be held in its uppermost

position at a relatively low pressure and the press is conditioned for another cycle of operation.

In the present instance the combined area of pullback pistons 23 and 24, is equal to the area 5 of piston 18. Therefore, no compensating device is necessary to take care of the differential volumes of fluid utilized in the system as would be the case in the event these areas were unequal.

10 It therefore is seen that a simple and highly efficient control mechanism has been provided. After each cycle of operation the platen is held in its uppermost position at a relatively low pressure, and consequently a great saving in the 15 power necessary to operate the pump is effected.

While the embodiment herein shown is admirably adapted to fulfill the objects primarily stated, it is to be understood that the invention 20 is not to be limited to this embodiment, since it 20 may be embodied in other forms, all coming within the scope of the claims which follow.

What is claimed is:

1. In a device of the class described, the combination of a variable discharge pump, stroke 25 adjusting elements for said pump, means for actuating said stroke adjusting elements to different positions of adjustment, said means comprising a cylinder having a piston operating therein, a rod operatively connecting said piston 30 to said stroke adjusting elements, an auxiliary pump constantly connected to the connecting rod end of said cylinder, an adjustable control valve, fluid conducting means connecting said auxiliary pump to said valve, fluid conducting means connecting said valve to the head end of said cylinder, means for so adjusting said valve that fluid from said auxiliary pump flows to the head end of 35 said cylinder, whereby the said piston operating therein actuates said stroke adjusting elements 40 toward neutral position, means for disabling said last mentioned means, and means for adjusting said valve to a second position of adjustment to disconnect said auxiliary pump from the head end of said cylinder and to connect the latter to 45 exhaust, whereby the pressure from said auxiliary pump acting on the connecting rod end of said piston effects actuation of said stroke adjusting elements in the reverse direction to increase the discharge 50 of said variable discharge pump.

50 2. In a device of the class described, the combination with a fluid motor, of a variable stroke pump for actuating said motor, stroke adjusting elements for said pump, means for actuating said stroke adjusting elements to different positions of adjustment, 55 said means comprising a cylinder having a piston operating therein, a rod connecting said piston to said stroke adjusting elements, an auxiliary pump constantly connected to the connecting rod end of said cylinder, an adjustable control valve, fluid conducting means connecting said auxiliary pump to said valve, fluid conducting means connecting said valve to the head end of said cylinder, means actuated by said motor when approaching its normal position for 60 so adjusting said valve that fluid from said auxiliary pump flows to the head of said cylinder whereby the said piston operating therein actuates said stroke adjusting elements toward neutral position, means for actuating said fluid motor in the reverse direction, whereby the said 65 means actuated thereby is moved out of operative relation with said valve, means for adjusting said valve to a second position of adjustment to disconnect said auxiliary pump from the head end of 70 said cylinder and to connect the latter to ex-

haust, whereby the pressure from said auxiliary pump acting on the connecting rod end of said piston effects actuation of said stroke adjusting elements in the reverse direction to increase the discharge of said variable discharge pump.

5 3. In a device of the class described, the combination with a fluid motor, of a variable stroke pump for actuating said fluid motor, a reversing valve for controlling the operation of said fluid motor, stroke adjusting elements for said pump, 10 means for actuating said stroke adjusting elements to different positions of adjustment, said means comprising a servo motor operatively connected to said stroke adjusting elements, said servo motor having a piston operating therein, 15 the opposite ends of said piston being of unequal areas, an auxiliary pump constantly subjecting the end of said piston of smaller area to pressure, an adjustable control valve, fluid conducting means connecting said auxiliary pump to said 20 valve, fluid conducting means connecting said valve to the end of the cylinder adjacent the larger end of said piston, abutment means actuated by said fluid motor adapted to so adjust said valve when said fluid motor approaches its 25 normal position of adjustment, that fluid from said auxiliary pump flows to the end of said piston of larger area, whereby the latter actuates said stroke adjusting elements toward neutral position, said abutment member moving out of 30 engagement with said control valve upon movement of said fluid motor in the reverse direction, means functioning to adjust said valve to a second position of adjustment to disconnect said auxiliary pump from the end of said piston of larger 35 area and to connect the latter to exhaust, whereby the fluid pressure in said auxiliary pump acting on the end of said piston of smaller area effects actuation of said stroke adjusting elements in the reverse direction to increase the discharge 40 of said variable discharge pump.

4. In a device of the class described, the combination with an hydraulic press, having a movable platen, of a variable stroke pump for actuating said platen, stroke adjusting elements for said pump, means for actuating said stroke adjusting elements to different positions of adjustment, said means comprising a cylinder having a piston operating therein, a rod operatively connecting one end of said piston to said stroke adjusting 50 elements, an auxiliary pump constantly connected to the connecting rod end of said cylinder, an adjustable control valve, fluid conducting means connecting said auxiliary pump to said valve, fluid conducting means connecting said valve to the head end of said cylinder, means actuated by said platen when approaching its normal position for so adjusting said valve that fluid from said auxiliary pump flows to the head end of said cylinder whereby the said piston operating 55 therein actuates said stroke adjusting elements toward neutral position, means for actuating said platen in the reverse direction whereby the latter is moved out of engagement with said valve, means for adjusting said valve to a second position of adjustment to disconnect said auxiliary pump from the head end of said cylinder and to connect the latter to exhaust, whereby the pressure from said auxiliary pump acting on the connecting rod end of said piston effects actuation of said stroke adjusting elements in the reverse direction to increase the discharge of said variable discharge pump.
